US0D1045938S

(12) **United States Design Patent** (10) Patent No.: **US D1,045,938 S**
(45) Date of Patent: ** Oct. 8, 2024

(54) **ELECTRIC EXCAVATOR**

(71) Applicant: **JiangSu XCMG Construction Machinery Research Institute LTD., Jiangsu (CN)**

(72) Inventors: **Hailin Huang**, Jiangsu (CN); **Liwei Xiao**, Jiangsu (CN); **Wanzhu Pei**, Jiangsu (CN); **Yueji Liu**, Jiangsu (CN)

(73) Assignee: **JiangSu XCMG Construction Machinery Research Institute LTD., Jiangsu (CN)**

(**) Term: **15 Years**

(21) Appl. No.: **29/892,558**

(22) Filed: **May 18, 2023**

(30) **Foreign Application Priority Data**

Nov. 30, 2022 (CN) 202230802909.4

(51) LOC (14) Cl. **12-09**

(52) U.S. Cl.

USPC **D15/22; D15/25; D15/24**

(58) **Field of Classification Search**

USPC **D15/10, 22-26, 28, 30**

CPC **E02F 3/32; E02F 3/76; E02F 3/40; E02F 3/325; E02F 3/352; E02F 3/384; E02F 3/425; E02F 3/437; E02F 3/627; E02F 3/964; E02F 9/163; E02F 9/0858; E02F 9/0875; E02F 9/2045; E02F 9/006; E02F 9/0808; E02F 9/0833; E02F 9/2004; E02F 9/207; E02F 9/2091; E02F 9/2246; E02F 9/2292; E02F 9/0086; E02F 9/18; F01N 13/001; F01N 2590/08**

CLAIM

The ornamental design for an electric excavator as shown.

DESCRIPTION

FIG. 1 is a perspective view of an electric excavator showing our new design;

FIG. 2 is another perspective view thereof;

FIG. 3 is another perspective view thereof;

FIG. 4 is another perspective view thereof;

FIG. 5 is a front view thereof;

FIG. 6 is a rear view thereof;

FIG. 7 is a left side view thereof;

FIG. 8 is a right side view thereof; and,

FIG. 9 is a top view thereof.

1 Claim, 9 Drawing Sheets
